UNITED STATES PATENT OFFICE.

HARVY BURSON, OF WICHITA, KANSAS, ASSIGNOR OF ONE-THIRD TO JOHN H. ELSPASS AND JOEL H. WHEELER, OF PUEBLO, COLORADO, JOHN M. WARE, OF ARKANSAS CITY, KANSAS, AND THOMAS RUSSELL, OF PUEBLO, COLORADO.

ORE-CRUSHING MILL.

SPECIFICATION forming part of Letters Patent No. 518,563, dated April 17, 1894.

Application filed June 13, 1892. Serial No. 436,618. (No model.)

To all whom it may concern:

Be it known that I, HARVY BURSON, a citizen of the United States of America, residing at Wichita, in the county of Sedgwick and State of Kansas, have invented certain new and useful Improvements in Ore-Crushing Mills, of which the following is a specification, reference being had therein to the accompanying drawings and the letters and figures of reference thereon, forming a part of this specification, in which—

Figure 1. is a top plan view, showing above a central horizontal line, the complete structure and below said line, the roll housings in horizontal section; Fig. 2. a top plan of the mill pedestal, and bed supporting spider thereon, and also the drive pulley and pinion for operating the mill bed; Fig. 3. a side elevation of the mill, representing portions thereof in vertical section, to more clearly show construction; Fig. 4. a detailed section of the mill crushing bed; Fig. 5. a detailed perspective of one of a series of plates for clamping screen plates to said bed, and Fig. 6. a similar view of one of a series of said screen plates.

This invention relates to certain improvements in ore crushing mills, designed more especially for crushing and pulping quartz and ores, and consists in the construction and arrangement of parts, which improvements are fully set forth and described in the following specification and pointed out in the claims.

Referring to the drawings A represents a pedestal, preferably made of wood timbers as shown.

E represents a cast iron spider having fine radial arms, which arms are provided at each end portion with heads 4 to which bar iron housing uprights 1 are secured, by bolts as shown, and terminate with lugs 5, by means of which the spider is bolted to the pedestal, by placing bolts through corresponding holes of both lugs and pedestal.

V is an annular V shaped ball track of the said spider and a are a series of metal balls arranged in said hollow track as shown.

S' represents a shaft boxed to the pedestal A, through the agency of boxes D, D, and is provided at its inner end with a pinion 6 and at its outer end with a drive pulley I.

B represents the ore crushing bed, of the mill, and is made circular in form and open at its central portion and has secured to its under surface, by means of cap screws, an annular casting K having formed therein an annular ball track V', inverted and conforming to that shown at V of the spider, which inverted track portion rides upon the balls a and thereby rotatably supports the bed B. Said annular casting K is further provided, about, and adjacent, the track V' with a bevel gear 9, which when the bed is thus set, meshes with pinion 6, and by such arrangement, the bed B is caused to rotate horizontally, by driving said pinion; being carried during such rotary circuit on the balls a.

The bed B is provided on its upper side with two annular concentric flanges F and F', the latter being that of the less diameter, and with an annular inclined ledge L, adjacent flange F and forming the margin of the bed, and between said flanges is formed an annular crushing trough having a radially inclined bottom, as shown, and has laid in said bottom upon a spelter bed B'' (see Fig. 4,) a chilled cast bed plate B', or said bed may be made of a plurality of sections laid to register at their meeting ends, and thus serve as would a single plate; the spelter which is placed under said chilled bed plates B', is placed as stated, after the said plates have been adjusted to their proper position by means of some temporary supports, by first heating it until it becomes a molten mass, and then pouring it into the space between the bed and said plates, when by such means of placing, it fills the entire space between said bed and plates, and when cooled gives a solid and uniform support to plates B' which exactness of support would be difficult to attain otherwise. The bed B is further provided with a series of equidistant upright portions 13, as shown in Fig. 4, and has arranged spanning the spaces between said uprights a series of screen plates, shown at 10 made with their center portion removed and supplanted with a screen 12 of wire fabric or other suitable material, which screen-plates are thus held into position by means of clamping plates 11 which are placed to clamp the

100

ends of said screen plates, and thus held by means of screws or bolts, as shown in Fig. 3.

R represents the crushing rolls of the mill, there being five in number, and each made with a bevel face corresponding with and adapted to ride upon the crushing bed B' of bed B, each roll being provided with a shaft S extending each way therefrom, which are journaled at each end in the bearings 3, which are housed in the uprights 1, 1, said journal bearings 3 being made respectively, in two parts, and the lower part of each bearing is supported in contact with the journal by means of a coil spring 7 which is sleeved upon the upright shank, or stem, of a supporting block 8, and engages the bearing about a depending lug of the bearing, which holds it seated; the block 8 resting in the upper cup shaped side of head 4 of the spider arm, (see Fig. 3.) The purpose of the springs 7 is, to provide a yielding support for the journal bearings of the crushing rolls, so that when the pressure is released from said bearings, by turning back the pressure screws, said springs will automatically raise the crushing rolls off the crushing bed a distance limited by the supporting power of said springs, or so the rolls will but lightly engage the bed, and also by means of said springs the lower portion of said journal bearings, which are essential in holding a lubricant for the journals, are at all times and at all adjustments yieldingly held in contact with the journals to properly supply them with, or prevent the free escape of, a lubricant otherwise furnished.

Arranged between the upper end of each pair of housing uprights 1-1 is a cast block J, held by means of cross-bolts; each said block being provided, through its vertical center portion, with a screw-threaded hole through which is turned a pressure screw 2, which is socketed at its lower end in a cushion cap c', which is arranged to slide vertically between the housing uprights, and c is a rubber cushion arranged interposed between said cushion cap and the upper journal bearing 3, as shown. Each housing of the mill is thus provided with a pressure screw and cushion c, which are for the purpose of imposing a yielding, but heavy pressure upon the journals of shafts S, and hence a like pressure of the rolls R upon the crushing bed B'; the pressure screws 2 serving as a means of regulating such pressure.

M. represents tie-bars which are arranged connecting and tying together the upper end of the outer series of housings, and m' are a similar set of tie-bars arranged connecting and tying together the outer and inner housings, being arranged in cross manner, as shown, and secured, jointly, by bolts placed through corresponding holes of their end portions, and through the blocks J of the uprights, or housings.

H is a hopper arranged at one side of the mill, into which the ore, to be crushed, is placed and H' is a chute of said hopper ar-

ranged to conduct the ore to and upon the crushing bed B', and G is a vertically adjustable gate of said chute for regulating the flow of ore to the bed.

W represents an annular water pipe arranged centrally over bed B, on the bars m' and held in position by being clipped to said bars, as shown, and W' is a supply pipe leading from said annular pipe, to some source of water supply, and has interposed therein a valve W'' for regulating the supply to the said annular pipe, and Z (see Fig. 3,) are down lead pipes smaller than said annular pipe, and connected with and depending from said annular pipe for conducting water to and upon the crushing bed B', for the purpose of supplying water to the ore during the crushing thereof, in order that when crushed a pulp may be made, which pulp is discharged, through the side screens of the bed flange, after a sufficient quantity has been made, as rapidly as it raises to said screen, and from said screen it flows down upon and from the ledge L of the bed B, and P is an annular copper pan, or trough arranged about under said ledge, and is, in use, charged with quick-silver, and upon such deposit of quick silver said pulp is discharged, which permits the metal particles to settle therein while the remaining portion of the pulp is washed away. Said annular pan P is made with its bottom inclining each way from a given point to a given opposite point where it is provided with a cross-partition, as shown at P' in Fig. 1, and in the bottom of each terminal part, either side of said partition is a drawing-off hole P' which are fitted with plugs, to retain the quick silver when operating the mill, and P'' are spouts arranged below said holes for conducting the discharge from said holes, when their plugs are removed, to some suitable receptacle for that purpose.

In operation a belt is applied to pulley I, from source of power, which through the agency of pinion 6 drives bed B. Ore is fed to the crushing bed from the chute of the hopper, and as the bed travels, on its circuit, the ore is carried about therewith, and under the rolls R, which, by reason of the weight of the rolls and the pressure brought to bear to hold them down upon the bed, crushes the ore, the ore coming under each roll in its order, which, at each roll action assists in such crushing until finally it is thoroughly crushed, and as the flow of water upon the bed is continuous, a pulp is made, which, as rapidly as it becomes sufficiently fine flows off with the overflow water, while the coarser particles remain until they become reduced and sufficiently fine to likewise flow off.

Having thus described my invention, what I claim as new and useful, and desire to secure by Letters Patent, is as follows:

1. The combination, in the mill described, of the pedestal, the spider fixed upon the pedestal, and provided with the radial arms, having the heads to which the housing up-

rights are secured, and with the grooved ball track; the housing uprights and their connecting head blocks, and tie bars; the rotatable crusher bed mounted on balls arranged to travel in said spider track; the gear mechanism for driving said bed; the crushing rolls mounted on shafts journaled in said housings, by means of vertically sliding bearings, and the pressure screws and interposed cushions, for imposing a yielding and variable pressure of said rolls upon the crushing bed, substantially as and for the purpose set forth.

2. The combination, in the mill described, of the crushing bed provided with equidistant upright portions arranged about upon

its side flange; of the screen plates placed to span the spaces between said upright portions; and of the plates, and screws, for holding said screens into position, substantially as set forth.

3. In the mill described, the combination with the ore crushing bed of the chilled plate or plates arranged to form the wearing surface of said bed; and an interposed bed of spelter, or like material, substantially as specified.

HARVY BURSON.
